UNITED STATES PATENT OFFICE.

JOHN F. MORSE, OF CHICAGO, ILLINOIS.

DESIGN FOR A SCARF-PIN.

SPECIFICATION forming part of Design No. 16,719, dated June 1, 1886.

Application filed April 12, 1886. Serial No. 198,644. Term of patent 7 years.

To all whom it may concern:

Be it known that I, JOHN F. MORSE, a citizen of the United States, residing in Chicago, in the county of Cook and State of Illinois, have invented a new and original Design for Scarf Pins, of which the following is a specification.

This invention relates to a new design for scarf-pins; and it consists of an ornamental head for such pins, formed in conventional representation of a cigar.

It further consists in the design for the head of a scarf-pin, consisting in a cigar-shaped ornament having a conventional representation of fire at its lighting end.

It further consists in the design for the head of a scarf-pin, consisting in a cigar-shaped ornament having conventional representation of both fire and ash.

In the accompanying drawing, which forms a part of this specification, my design is shown in front elevation, A representing the pin, and B the head or ornament to which the de-

sign relates. This head is made in conventional representation of a cigar. The imitation of fire is shown at C, and the imitation of both fire and ash is shown at C and D, respectively.

I claim—

1. The design for scarf-pins herein shown and described, the same consisting of a pin having an ornamental head shaped in conventional representation of a cigar.

2. The design for scarf-pins herein shown and described, the same consisting of a pin having an ornamental head in conventional representation of a cigar and its fire, to give the appearance of ignition.

3. The design for scarf-pins herein shown and described, the same consisting of a pin having an ornamental head in conventional representation of a cigar and its fire and ash.

JOHN F. MORSE.
